UNITED STATES PATENT OFFICE.

FREDERICK THEOPHILUS AIKINS, OF TORONTO, CANADA.

MUCILAGE-SCRAPER.

SPECIFICATION forming part of Letters Patent No. 448,492, dated March 17, 1891.

Application filed September 6, 1890. Serial No. 364,180. (No model.)

To all whom it may concern:

Be it known that I, FREDERICK THEOPHILUS AIKINS, accountant, of the city of Toronto, in the county of York, in the Province of Ontario, Canada, have invented a certain new and Improved Device for Removing Surplus Mucilage from a Mucilage-Brush, of which the following is a specification.

The object of the invention is to make a simple device which may be detachably connected to any mucilage-bottle, and which by gentle pressure will remove any superfluous mucilage from the mucilage-brush as it is withdrawn from the bottle; and it consists, essentially, of a piece of spring sheet metal formed to fit into the mouth of the bottle and having two fingers extending from it, with a jaw formed on the end of each finger, the sheet metal being shaped so as to bring the jaws squarely opposite to each other, and the fingers set so that their spring action shall force the jaws together with sufficient force to remove any superfluous mucilage on a brush drawn between them, substantially as hereinafter more particularly explained.

Figure 1 is a view of a mucilage-bottle provided with my attachment. Figs. 2, 3, 4, 5, and 6 are perspective details showing alternative forms of the attachment.

Although I prefer to make my attachment out of a single piece of sheet metal, it might readily be made in more than one piece joined together, and any kind of spring metal would answer the purpose.

In the drawings, A represents the bottle, and B a strip of sheet metal shaped to fit into the neck or mouth of the bottle and having sufficient spring-pressure to retain it in position. Two fingers C extend from the strip B and on the end of each finger a jaw D is formed. It will be observed that at the point where the fingers C join the strip B the said strip is set inwardly, so as to bring the fingers and jaws D squarely opposite to each other. Of course this set would not be necessary if the jaws were brought exactly in the center of the bottle A; but I prefer to have the jaws D nearer the side of the bottle, and consequently the set mentioned is necessary and important. It will also be observed that

in each of the alternative forms shown the fingers C are shaped so that the brush will not come in contact with them while being drawn between the jaws. One end of one of the jaws D has a flange a formed on it to about 55 against the interior of the neck of the bottle A and against which the end of the other jaw abuts. In this way the bottle acts as a stop to allow the brush to be slipped between the jaws without pushing the device out of position. The other ends b of these jaws are bent outwardly, so as to permit the ready insertion of the brush between the said jaws.

From this description and on examination of the drawings it will be seen that superfluous mucilage may be easily and quickly removed without fear of injuring the mucilage-brush, and as the attachment is readily removed from the bottle it is easy to keep it clean.

What I claim as my invention is—

1. A strip of metal B, detachably connected to the neck of a bottle A and having fingers C extending from it, jaws D being formed on the ends of the said fingers, which fingers are set so that the tension of their spring shall cause the jaws to press elastically toward each other, substantially as and for the purpose specified.

2. A strip of metal B, detachably connected to the neck of a bottle A and having fingers C extending from it, jaws D being formed on the ends of the said fingers, which fingers are set so as to leave a space between them and cause the jaws to press elastically toward each other, substantially as and for the purpose specified.

3. A strip of metal B, detachably connected to the neck of a bottle A and having fingers C extending from it, jaws D being formed on the ends of the said fingers, the strip B at its connection with the finger C being set inwardly, so as to bring the jaws B squarely opposite to each other, substantially as and for the purpose specified.

Toronto, August 21, 1890.

FREDERICK THEOPHILUS AIKINS.

In presence of—

CHARLES C. BALDWIN,
W. G. MCMILLAN.
